DESIGN FOR A COAT

Emily Wilkens, New York, N. Y.

Application August 24, 1946, Serial No. 132,836

Term of patent 7 years

(Cl. D3—4)

To all whom it may concern:

Be it known that I, Emily Wilkens, a citizen of the United States of America, residing in New York city, county of New York, and State of New York, have invented a new, original, and ornamental Design for a Coat, of which the following is a specification, reference being had to the accompanying drawing, forming part thereof.

Fig. 1 is a front view of a coat, showing my new design.

Fig. 2 is a rear view thereof.

I claim:

The ornamental design for a coat, substantially as shown.

EMILY WILKENS,
